CHAIN GRATE STOKER

William M. Duncan, Alton, Ill.

Application December 28, 1931

Serial No. 583,571

3 Claims. (Cl. 110—40)

This invention relates to certain new and useful improvements in chain grate stokers, the peculiarities of which will be hereinafter fully described and claimed.

5 The main objects of my invention are first, to improve the construction and operation of my prior Patent No. 1,145,573; second, to provide a resilient seal for dampers; third, to provide multiple dampers which are more easily operated in 10 opening and closing positions; fourth, to provide end closing walls forming a draft chamber of restricted size corresponding to the active grate surface, for regulating the air currents entering said chamber and more evenly disposing them to 15 the multiple dampers selectively delivering air to the active grate surface; fifth, to obstruct the passage of air longitudinally under and through the strands of stoker chains, and substantially confine the upward draft to the selected portions 20 of grate surface above the open damper or dampers; sixth, to provide temporary storage compartments above the dampers for the coal particles sifting through the grate and collecting on the closed dampers; and seventh, to provide other 25 features of construction and operation herein- after described and claimed.

Stokers equipped with dampers in accordance with my prior Patent No. 1,145,573, have proved remarkably efficient in saving fuel by the elimination of excess air passing upwardly through the 30 grate, but on account of the construction of those dampers a perfect seal could not be maintained, due to slight warping of the damper plate, irregularities of contiguous castings, or slight 35 inaccuracies of workmanship. It has also been found that my prior form of center-pivoted dampers were often difficult to open, due to fine coal particles sifting through the grate and filling the space between the closed damper and the 40 lower plane of the grate strands.

It is to the elimination of these objectionable features and the provision of improved construction and operation, that my present application relates.

45 Not only on boilers supplying steam for heating buildings, but on boilers supplying steam for power generation as well, the load is by no means constant. To make the active grate surface comparable with the boiler load that is to be carried, 50 dampers or closures are provided by which air can be excluded, limited, or freely admitted, selectively to various areas of the grate. To be fully effective, especially when "banking" a fire, (that is, maintaining a bed of glowing coal with- 55 out producing steam in the boiler over a pro-

tracted period), it is essential that the dampers close so tightly that no air that tends to burn out the coal will pass by them. This desired effect is obtained by the construction which is the subject of my present application.

60 In the accompanying drawing in which like reference numerals indicate corresponding parts,

Fig. 1 represents a longitudinal section of a chain grate stoker on a vertical plane inside the stoker sides;

Fig. 2, an enlarged sectional view of the damper seals; and

Fig. 3, a similar view of a modification of the damper and seals.

70 Referring to the drawing, the numeral 1 designates the stoker drive shaft on which are mounted sprockets 2 for imparting longitudinal travel to chain links 3, pivoted together in longitudinal strands passing over rear drums 4 mounted on a rear shaft 5. These sprockets and drums separate the strands into upper and lower rows of traveling grate. A suitable stoker hopper A delivers the coal to the upper row, and it is carried under the front wall B of the furnace to constitute the fuel bed on the active grate surface.

75 I-beams or other forms of transverse bars 7, connect the stoker sides 11 and support longitudinal carry or skid bars 14 on which ride the grate strands. Filler bars 13 substantially equal in height to the carry bars, are mounted on said bars 7 and seal the space directly below the grate strands from longitudinal air passage. The flow of air longitudinally between the grate strands themselves is obstructed by any suitable lateral projections such as at 15 extending into the 80 spaces between the strands and forming baffles on the links.

85 Directly under the seal bars 13 and preferably resting on the transverse supports 7, are mounted thin, resilient metal strips 12 extending between the stoker sides 11 and projecting laterally on each side beyond the supports 7 and seal bars 13. The projecting side edges of these resilient strips are preferably inclined downward more or less as shown in the figures, and form 90 frames that define upward draft openings to the upper row and provide resilient edges for said seal bars 13.

95 In each of these openings are mounted one or more damper plates 8, each fastened near one side edge to rods 9 by means of lug castings 10 or otherwise. The rods are oscillatably pivoted in suitable bearings in the stoker sides, and are mounted laterally beyond the adjacent resilient edge of the draft frame, so that the damper plate 100

will engage and flex both said resilient edges in moving to closing engagement with their underside, and substantially seal the draft opening from any upward draft to that portion of the grate above the damper when closed.

The coal particles sifted thereon while any damper is closed, will be discharged when the damper is inclined downward to open position, and such opening is readily effected since all parts of the loaded damper plate swing downward from its pivotal axis.

(In my prior patent above mentioned, the packed coal deposit on the upper half of the center-pivoted damper was raised and pressed against the grate strands, thus obstructing operating the damper.)

My present dampers are opened independently more or less, according to the amount of air it is desired to admit to the grate surface above the respective dampers. Any deposit of coal particles that may lodge on a slightly inclined damper may be dumped before closing; or the inclined resilient edges will cut down through such deposit and effect sealing engagement with the damper when raised to its closed position.

In Fig. 3 these sealing edges are inclined more than in Figs. 1 and 2, to accord with the normal closed inclination of the double damper plates mounted in the same draft opening. In this modification, the damper plates contact with the resilient side edges and also with each other in their inclined closing position, and form a hopper compartment adapted to store more sifted coal particles temporarily than the form shown in Figs. 1 and 2. Each of the double plates in Fig. 3 is pivotally mounted near its upper side edge, and the lower side edge of one plate member is bent laterally as shown and forms a resilient side edge 12' for sealing contact with the other plate member when its bent edge engages the lower plate in various upward adjustments of both plates. Pressure is exerted on the lower plate and positive sealing engagement between the two plates is obtained by a crank rod 20 and link connection 21, or other means.

While I have shown and described the inclined edge of the strip 12 as the resilient member on the draft frame, the other damper member may have a resilient edge as at 12' in Fig. 3, or otherwise, but my preferred form is that shown in Figs. 1 and 2.

Between the upper and lower rows of grate strands at the front and rear ends of the active grate surface, vertically disposed plates 22-22'

55

60

connect the stoker sides 11 and form with said sides and regulating dampers, a draft chamber below the active grate surface. Resilient transverse plates 23-23', horizontally mounted by their outer ends to the bottom of said draft chamber, connect the stoker sides and are disposed substantially in contact with the under side of the lower row adjacent to said end closing plates. These plates extend toward each other and form a partial bottom for said chamber by obstructing the air draft between the links of the lower row near the end closing plates.

Above these bottom plates, corresponding upper plates 6-6' are adjustably mounted substantially in contact with the upper surface of the lower row, and have vertical web portions 24-24' slidably engaging the end closing plates 22-22'. Said upper plates are provided with double link connections 25-25', which are merely anchors, and form flexible seals in conjunction with the bottom plates, for preventing the passage of air currents through the front and rear ends of the stoker into or out of said draft chamber, and promoting even distribution of the air currents to the regulating dampers at the top of said chamber.

I claim:

1. A stoker comprising an endless grate, a seal bar and a support therefor located below the upper run of said grate, a resilient plate interposed between said bar and support and projecting laterally therefrom, and an adjustable damper mounted below said plate and yieldably contacting therewith in closed position.

2. A stoker comprising an endless grate, transverse seal bars filling the space directly below the upper run of said grate and supports therefor disposed at spaced intervals below said grate, plates interposed between said bars and supports and having resilient edges projecting laterally therefrom on each side, and adjustable dampers mounted below said plates and making yieldable contact therewith in closed position.

3. A stoker comprising an endless grate, transverse seal bars and supports therefor disposed at spaced intervals below the upper run of said grate, plates interposed between said bars and supports and having projecting resilient edges inclined downwardly on each side, and adjustable dampers mounted in said intervals and making yieldable contact with said edges when raised to closed position.

WILLIAM M. DUNCAN.
